[57] CLAIM

The ornamental design for a restaurant building, as shown and described.

DESCRIPTION

FIG. 1 is a top plan view of a restaurant building showing my new design, which includes three radially extending arms spaced at equal angles from one another around the periphery of the building;

FIG. 2 is an elevational view thereof, looking directly at the end of one of the arms; and

FIG. 3 is an elevational view thereof taken at an angle of sixty degrees to the elevational view of FIG. 2.
